APRON

Filed Dec. 31, 1929

UNITED STATES PATENT OFFICE

SOPHRONIA ISABELLA ESTES, OF MIAMI, FLORIDA

APRON

Application filed December 31, 1929. Serial No. 417,720.

This invention relates to an article of wearing apparel and has particular reference to an apron to be worn by ladies beneath the slip or petticoat and the dress.

5 The apron is especially adapted for use as a shield to protect the slip and dress of the wearer against the deteriorating effects of perspiration, and will further aid in the prevention of the dress and slip sticking to the 10 body or becoming caught in the crotch, as is often the case when one rises from a seated position and which, as is appreciated, presents an embarrassing and unsightly appearance. It also serves as a sanitary and a 15 shadow proof apron, and it obscures the form of the pelvic parts of the body.

The invention comprehends an apron especially adapted for the purpose above mentioned, which is suitably weighted so that the 20 wearer arising from a seated to a standing position the apron will swing outwardly, thus leaving the slip and dress in a neat and smooth position out of contact with the body.

Other objects and advantages of this invention will become apparent upon a study 25 of the following description taken in connection with the accompanying drawings wherein:

Figure 1 is a plan view of an apron embodying the features of the present invention and looking at the apron toward that side 30 next to the wearer.

Figure 2 is a detail sectional view taken substantially on the line 2—2 of Figure 1,

35 Figure 3 is a similar view taken substantially on the line 3—3 of Figure 1.

With reference more in detail to the drawings, it will be seen that my improved apron may be formed of any suitable material of 40 suitable length and width and is designated generally by the reference character 5. Stitched to the apron 5 along the opposite sides thereof inwardly from the marginal edge of the apron is a stiffening strip of 45 tape 6.

Stitched to the upper edge of the apron 5 is a body band or girdle 7, which girdle 7 extends about the waist of the wearer and the apron 5 depends therefrom across the back 50 and crotch of the wearer. Additional secur-

ing tapes 8 extend from opposite sides of the apron 5 adjacent the upper end of the apron, and these strips 8 extend across the hips of the wearer and at their free ends may be secured together preferably at the side of 55 the wearer.

In this connection also the free end of the supporting girdle 7 may also be tied or otherwise secured together at the sides of the wearer thus preventing any bunching or unsightly 60 appearance at the front of the wearer.

A relatively small sack 9 has disposed therein a suitable weight 10, and at its upper end, the sack 9 is stitched as at 11 to the apron 5 inwardly from the longitudinal edges of the 65 apron below the transverse centre line of the apron.

As shown to advantage in Figure 1, obviously being stitched in this manner the sack 70 is adapted to swing for a purpose to be hereinafter made manifest.

Extending along the lower or bottom edge of the apron and also the lower corners of the apron is a second weight strip designated generally by the reference character 12. The weight strip 12 comprises a suitable elongated strip 13 of suitable fabric stitched along its opposite longitudinal edges to the lowermost portion of a second strip 14 of a length 75 equal in length to the length of the strip 13 80 but of a greater width than the strip 13 as shown to advantage in Figure 3.

The strips 13 and 14 both stitched together form an elongated tube adapted for the reception of a plurality of spaced weights 15, and the upper longitudinal free edge of the outer strip 14 is stitched as at 16 to the lower edge portion of the apron 5 inwardly from the marginal edge of the apron, the tube or 90 weight strip 12 being so stitched as to conform to the lower edge and lowermost corners of the apron 5 as shown to advantage in Figure I.

Thus it will be seen that also the weight 95 strip 12 is adapted for swinging movement in the same manner as the weight sack 9.

It may be also noted that the girdle or supporting waist band 7 may be made of two or more plies stitched together along their lon- 100

itudinal edges by stitching 17 and 18 respectively.

In actual practice the apron as before intimated will through the medium of the belt 5 or girdle 7 and the hip tapes 8 be secured to the body of the wearer so that the apron portion 5 proper will depend from the waist line across the back of the wearer, said apron to be worn beneath the nether garments of the 10 wearer.

Thus it will be seen that the weight 10 in the sack 9 hangs substantially perpendicular and by the swinging movement of the sack 9 the weight will fall toward the body 15 while the wearer is walking and away from the body upon the rising of the wearer from a sitting to a standing position.

The weight strip 12 along the lower edge of the apron will fall outwardly away from 20 the body when the wearer arises thus pulling the skirt or nether garment from the body should the skirt or nether garment be caught or stuck to the body as may be occasioned by perspiration.

25 Thus the first pull exerted upon the apron will come from the lower weight 12 while the weight in the sack 9 or the upper weight gives the second pull, and thus the weight in the lower edge and in the intermediate portion of the apron will coact to always move the apron away from the body when the wearer rises and consequently the clothing or nether garments of the wearer will likewise be moved away from the body and the danger 35 of the clothing becoming stuck to the body or caught in the crotch of the wearer will be eliminated.

When wearing an apron of this character, as will be appreciated from the above, the 40 wearer will have the assurance that her clothing will at all times fall free from her form no matter how long she may have remained seated or how much she may have perspired.

45 Preferably the apron is to be worn over the conventional corset or girdle and under the "dress slip", thus the apron acts as a shield to prevent contact of the outer garment with the body, and the material of which the apron is made will be such that the apron will be 50 shadowproof, and the material of the apron may also be of such a nature as to utilize the apron for sanitary purposes.

55 As shown in the drawings, the apron gradually tapers toward its upper end and to accomplish this tapering of the apron, the same adjacent its upper end may be gathered, such gathering of the apron being accomplished by providing suitable pleats, as suggested or in any other desired manner. This particular 60 feature of the apron is, of course, optional.

It is believed that from the foregoing description, taken in connection with the accompanying drawings, a clear understanding of the operation, utility and advantages of an 65 invention of this character will be had by

those skilled in this art without a more detailed description thereof.

Having thus described my invention, what I claim as new is:

An apron to be worn beneath the nether 70 garments of the wearer, and comprising a body portion, a waist encircling band carried by said body portion at the upper edge thereof, a relatively small sack stitched at its upper end to the apron inwardly from the opposite longitudinal edges of the apron and adjacent the lower portion of said apron, a weight in said sack, and a weight strip swingably secured to the apron and extending 75 along the lower edge of said apron.

80 In testimony whereof I affix my signature.

SOPHRONIA ISABELLA ESTES.
